ATTORNEY

UNITED STATES PATENT OFFICE.

JOSEPH H. TEMPLIN, OF READING, PENNSYLVANIA, ASSIGNOR, BY MESNE ASSIGNMENTS, TO THOMAS V. ALLIS, OF NEW YORK, N. Y.

DIE FOR USE IN MAKING BARBED FENCING.

SPECIFICATION forming part of Letters Patent No. 450,047, dated April 7, 1891.

Application filed August 13, 1888. Serial No. 282,554. (No model.)

To all whom it may concern:

Be it known that I, JOSEPH H. TEMPLIN, a citizen of the United States, and a resident of Reading, in the county of Berks and State of Pennsylvania, have invented certain new and useful Improvements in a Combination of Dies for Use in Machinery for Making Barbed Strips, of which the following is a specification.

10 This invention is an improved contrivance of dies for producing two barbed strips from one double blank strip by first punching pointed barbs at intervals along the middle of the double blank strip having retaining 15 connection at the base with the strip, bending said points into suitable lateral projection, and separating the uncut webs between the barbs, so as to divide the barbs so made alike between the two strips thus produced 20 out of the blank.

Referring to the drawings, Figure 1 represents face views of one arrangement of dies that may be employed to carry out my invention. Fig. 2 is a diagram of the blank strip, 25 showing the action of the dies on it. Fig. 3 represents face views of other or modified forms of dies that may be employed. Fig. 4 is a diagram of the strip, showing the action of the dies of Fig. 3; and Fig. 5 is a side elevation of dies, such as represented in Fig. 3, with the blank strip between them.

In the method of operation I punch pointed barbs *c* at intervals along the middle portion of the blank strip *a*, which is a plain flat 35 strip of metal of suitable width for two completed barb-strips *b*, so that they have retaining connection at their base with the strip by intervening uncut webs *d* left between each two barbs, and, also, so that the punching of 40 the barbs separates the rest of the blank between said webs into two parts, the points of said each two barbs being cut from close proximity in the blank; but the bases are distant from the next two the length of an uncut web 45 *d*, and the edges of the barbs are preferably parallel, except at the points. After thus cutting the barbs I bend them laterally to the strip for the required projection therefrom

by any approved benders, as *e f*, and then 50 separate the remaining uncut webs *d* by cutters, as *g h*, alternately in the lines of the different edges of the barbs, so that the making 55 of two strips is completed and the barbs are equally divided between them, two together, alternately on each strip, and the barbs of each couple are bent in opposite directions.

To cut the barbs I prefer to employ suitable punches *i* with corresponding counterparts *j*, adapted to cut parallel edged and center-pointed barbs, as shown in due succession, preferring to employ four in a gate for cutting four barbs at each operation, which punches may either be arranged in the order of Fig. 1 or of Fig. 3, as preferred, the former being a contrivance of two punches cutting 65 points together at the middle of the gate with one, each side cutting points reversely, and the latter being duplicate contrivances of two punches cutting points together and arranged side by side in the gate. Thus four barbs are 70 made, two on each barb-strip at each operation of the dies, and two are bent in one direction by one pair of the bending-dies and two in the opposite direction.

The method of operation herein described 75 is reserved for a separate application for a patent.

What I claim, and desire to secure by Letters Patent, is—

1. The combination of dies for producing 80 two barbed strips from one double blank strip, which consists of punching-dies *i j*, adapted for punching at intervals along the strip pointed barbs, as *c*, having retaining connection of the base with the strip, and 85 web-cutting dies, as *g h*, adapted for separating the uncut webs between the barbs along the lines of the respective edges of the barbs alternately, substantially as described.

2. The combination of dies for producing 90 two barbed strips from one double blank strip and bending the barbs laterally to the strips, which consists of punching-dies *i j*, adapted for punching at intervals along the strip pointed barbs, as *c*, having retaining 95 connection of the base with the strip, web-

cutting dies, as *g h*, adapted for separating the uncut webs between the barbs along the lines of the respective edges of the barbs alternately, and bending-dies, as *e f*, adapted for bending the barbs laterally to the strip, substantially as described.

Signed at New York city, in the county and

State of New York, this 2d day of May, A. D. 1888.

JOSEPH H. TEMPLIN.
